CLAIM

The ornamental design for a inclined side wall jewelry box, as shown and described herein.

DESCRIPTION

FIG. 1 Is a perspective view showing my inclined side wall jewelry box in the open position with the dotted lines showing being for illustrative purposes only for which no claim is made;

FIG. 2 Is a front perspective view of my inclined side wall jewelry box as shown in the closed position;

FIG. 3 Is a top plan view thereof;

FIG. 4 Is a bottom plan view thereof;

FIG. 5 Is a front view thereof;

FIG. 6 Is a rear view thereof; and,

FIG. 7 Is a left side elevational view thereof with the right side being a mirror image thereof.
